GROUND PAD

Martin N. Haller, Pittsburgh, Pa., assignor to the United States of America as represented by the Secretary of the Army

Application August 3, 1953, Serial No. 26,462

Term of patent 14 years

(Cl. D5—2)

To all whom it may concern:

Be it known that I, Martin N. Haller, a citizen of the United States of America, residing at Pittsburgh, Pennsylvania, have invented a new, original, and ornamental Design for a Ground Pad, of which the following is a specification, reference being had to the accompanying drawings forming a part hereof.

Fig. 1 is a top plan view of a ground pad, showing my new design;

Fig. 2 is a side elevation of the same;

Fig. 3 is an end elevation of the same; and

Fig. 4 is a perspective view on a larger scale of one of the resilient strips forming part of the ground pad, shown attached to a textile fabric backing sheet.

The bottom surface of the ground pad is not shown because it is substantially plain.

I claim:

The ornamental design for a ground pad, as shown and described.
